UNITED STATES PATENT OFFICE.

EDWIN CHILDREN, OF EAST DUBUQUE, ILLINOIS.

WHEEL-CULTIVATOR.

SPECIFICATION forming part of Letters Patent No. 434,765, dated August 19, 1890.

Application filed March 23, 1889, Serial No. 304,395. (No model.)

To all whom it may concern:

Be it known that I, EDWIN CHILDREN, a citizen of the United States, residing at East Dubuque, in the county of Jo Daviess and State of Illinois, have invented certain new and useful Improvements in Wheeled Cultivators; and I do hereby declare the following to be a full, clear, and exact description of the invention, which will enable others skilled in the art to which it appertains to make and use the same.

My invention relates to wheel-cultivators, but has more especial reference to those heretofore patented by me in the following Letters Patent, viz: No. 62,004, dated February 12, 1867; No. 159,550, dated February 9, 1875, and No. 334,641, dated January 19, 1886.

In the above-mentioned patents it will be understood that the front ends of the reaches, together with the yoke to which the forward ends of the plow-beams were hinged, were carried laterally on a track provided with rollers; but in my present construction I do away with the "track and rollers," and instead loosely suspend these ends with the yoke, whereby I am enabled to obtain not only a lateral, but also an upright or perpendicular, movement of the plow-beams, and also perpendicular movement of each beam separately.

The principal feature, therefore, of my invention consists of loosely suspending the forward ends of the plow-beams in such a manner that they are thus made capable of both horizontal and perpendicular movements; and the pressure or resistance of the shovels on the earth and the cut of the same in depth may be thus regulated with precision, and, further, by means of this novel suspension of the forward ends of the plow-beams the operator can use my cultivator more readily than has heretofore been the case in hard or soft soil, up hill or down, on the hillsides and in the widely-varying conditions of the "listed" corn, or conveniently in any work wherein a horizontal or perpendicular adjustment of the plow-beams and shovels becomes imperative. I can also obtain by these means a higher draft-point, a freer action of the double-trees, and also use a shorter beam.

My invention further relates to other but

less important details of construction, all of which will be more fully hereinafter described and claimed, and which are illustrated in the accompanying drawings, wherein like letters of reference indicate corresponding parts in each view, and in which—

Figure 1 is a side perspective view of a portion of my invention; Fig. 2, a rear perspective view of the same. Fig. 3, a sectional view of one of the reach-bars and a portion of one of the plow-beams, showing the connections between the reach-bars and axles and the plow-beams; Fig. 4, an enlarged perspective view of the connections between the reach-bars and the plow-beams, and Fig. 5, a similar view of the supporting-crane for the plow-beams. Fig. 6 is a perspective view of the yoke; and Fig. 7, the collar T, to which the chain is attached.

A represents the axle, to the ends of which are mounted the wheels, adapted to work on each side of the row. To this axle is attached the frame-work, consisting of the two oblique pieces *a a'* and the two flat connecting-pieces *b b'*, extending across the front portion of the said oblique pieces *a a'*.

Pivoted by means of a pin between the two flat connecting-pieces *b b'* of the main frame is the pole C, provided at its extreme rear end with a friction-roller *e*, adapted to bear on the flat metallic track *e'*, connecting the two oblique bars *a a'*. Near the rear extremity of the pole C, and on top of the same, is pivotally mounted a crotch or stirrup *f*, and the two branch parallel arms of said stirrup are provided with slots *f' f''* in each arm, and into these slots are inserted the pins *g g*, extending out on each side of an operating-lever D. This operating-lever is preferably provided with a number of these pins *g*, so that the fulcrum of the lever may be changed and the power thereby obtained nicely regulated, and the operator can more readily reach the lever, whether riding or walking. The rear portion of this operating-lever D is formed into a suitable spherical handle *g'*, adapted to be grasped by the driver or operator, and the forward end of this lever D is connected by means of an ordinary metallic link or connecting-rod *h* to a pivoting device *h'*, securely fastened to either one of the oblique braces *a a'*.

Beneath and to the under side of the axle A are pivoted the rear ends of the two reach-bars C' (illustrated in Fig. 3,) as follows: At the rear end of each reach-bar is securely fastened a flat metallic strip d, provided with a hole therein, through which a pin d' of smaller diameter extends. Surrounding this flat strip is a rectangular plate or box d'', acting as a brace for the lower portion of the pin d'. By means of this arrangement it will be seen that the reach-bars are capable of both a limited horizontal and vertical movement on the pins d'. At the forward portion of each reach-bar are securely fastened two flat metallic arms j j'—one on the top and the other on the bottom of each reach-bar—and pivoted between these two arms, by means of short integral metallic pins j² j², is a metallic sleeve J, encircling the metallic yoke E and loosely keyed to said yoke. This yoke E is preferably made from a single piece of metal and curved upward at the center so as to pass over the corn or whatever is to be cultivated.

On each side of the sleeve J, and also encircling the yoke E, is an integral arm L of the clevis F. The rear or main body portion L' of this clevis is rigidly fastened to the forward end of the upper side of the plow-beam by means of bolts. By means of the clevis and connections just described it will be evident that the front portion of the reach-bars may be moved in a horizontal direction by reason of the arms j j' being pivoted or hinged on the collar J, and that this horizontal movement of the front ends of the reach-bars will cause the yoke E to move in a like direction, and thereby carry the plow-beams at right angles with it in a similar direction by means of the clevis F. The outer extension of the sleeve J is encircled by another sleeve T of greater diameter, as shown in Fig. 7, which sleeve extends to the outer end of the yoke E, and, being open on its under side, extends on both sides of the arm L of the clevis F and fits closely around the outer end of the yoke E. This sleeve T is supplied upon one side with several slots e e, into which the projection E', which is made integral with the arm L of the clevis F, meshes with and prevents this sleeve from turning around on the yoke E. The object of having more than one slot formed in the sleeve T is to change the space between the plow-beams in order to operate the shovels near to or away from the plants to be cultivated, according as may be demanded by their condition. On the opposite side from the slots e e e of the sleeve T is a hook m, to which the chain, presently to be described farther on, is hooked. It will now be seen that the sleeve T while in operation is prevented from sliding upon the yoke E either to the right or left by means of a lug e'', cast on the extension of the sleeve J; but this does not prevent the sleeve T from turning upon the yoke E when desired.

Directly above the track e', and secured to the upper side of each oblique brace a a', is

a bar H, made, preferably, of wood, and extending some little distance beyond the outside of each brace. Rigidly secured to the upper side of this bar H, and a little to one side of the oblique braces a a', are the metallic uprights n n', arranged in pairs, as shown, and inclined slightly toward each other at their upper ends, and at the upper portion of each pair of uprights and extending from one upright to the other is a pivoting-pin n''. Extending backwardly from these uprights are the metallic locking-pieces o', each provided with a series of curved retaining-lugs o'' o'' on its rear portion and on the outside thereof. Pivot at its forward ends to these pins n'' is a preferably metallic lever I I, each provided with an opening p, adapted to be inserted over any one of the lugs o'' o'', so that each lever may be locked at any point in its path of movement. A chain q q' of any suitable construction, passing upwardly between the uprights n n' and over the bar H, connects the said levers I I with the before-mentioned hooks m, formed on the outward portion of the sleeve T. By this means it will be seen that either of the levers I may be raised or lowered and locked at any point on the lugs o'' o'' of the locking-pieces o o'. These movements of the levers will elevate and depress the forward ends of the plow-beams and reaches by means of the connecting-chains and by reason of the locking-pieces o o', and thus the elevation and depression of the forward ends of the plow-beams may be regulated with certainty.

The suspension of the forward end of the reaches a a' and yoke E by the chain q q' on the hook m of the sleeve T at a point just forward or near the hinged center of the forward end of the plow-beams greatly increases the tendency to hold the shovels down firmly and rigidly to their work, and also enables me to use a shorter beam and a higher hinge-point than would otherwise necessarily be required. It will now be apparent that by this suspension of the forward ends of the plow-beams and reaches through the means of the chains q q', attached at or near the said hinged center to the hook m and running back in a slightly oblique direction, the doubletree can be attached more conveniently farther back and nearer the axle, and its free movement will not be thereby interfered with through the means of the suspending-chains q q' or the curved yoke E, and this construction and arrangement lessens the obstruction to the outlook of the driver. It further enables the operator or driver, by raising or lowering the levers I I, to change the pitch or angle of the shovels while the cultivator is moving forward, and thus be enabled to meet the various conditions that may arise.

At the other end of the plow-beams, on the arms J J, are secured the metallic shovels, (not shown,) constructed as usual, and capable of being adjusted to any position in horizontal plane by any suitable device.

On the rear ends of the oblique braces $a a'$ are pivotally secured two peculiarly-constructed cranes for supporting the rear ends of the plow-beams. These cranes are preferably made as follows: The main supporting-casting r of this crane is pivotally supported to the rear ends of braces $a a'$ by means of two integral lugs $r' r'$, one placed above each of said braces and the other directly beneath the same, and both being pivoted to said braces $a a'$ by means of an ordinary pivoting-pin passing entirely through the same. On each side of the support r is a lug r'' , preferably made integral with the same and provided each with a horizontal slot r''' therein. Engaging with these slots or openings r^3 is a lug s , formed on each side of a right-angled lever L and made integral therewith. The short or vertical arm s' of the right-angled lever L is kept normally outward by means of a leaf-spring t , attached to the upper part of the support-arm, its free end extending downward and bearing against the arm s' , so that the said arm will thereby be kept parallel with said spring. The long or curved arm t' of this right-angled lever is provided at its rearward extremity with a hook t^2 for the purpose mentioned hereinafter. It will now be evident that when any downward strain is brought to bear on the horizontal arm t' it will cause said arm to be depressed, and the short arm will thereby be forced against the tension of the spring t , and by such means it will be apparent that the support offered by the support t^2 on the ends of the curved arm t' will be a very elastic one.

To each plow-beam, and rigidly fastened thereto, is an inverted bearing-box carrying within it an ordinary pulley-wheel u , and directly to the rear of each pulley is located a lever-and-ratchet device for locking the same, consisting as follows: A quadrant M is rigidly secured to each plow-beam, and is provided along its upper edge with a series of retaining-teeth v . The bearing-box carrying the wheel u may be cast with the quadrant M , and thus form one piece. Pivoted to the lower portion of each quadrant is a lever N , provided with a lug adapted to engage with any one of the retaining-teeth v of the quadrant M . This lever N is also provided with an arm v^2 and a hook v^3 at its forward end and made integral therewith. A chain w , connecting at one end with the hook t^2 and passing under the pulley-wheel u , is attached at its other end to a hook v^3 on the arm v' .

Connecting the rear portion of the pole C with one of the reach-bars is a connecting-rod i' , pivoted at one end to the lower side of the pole C and to the upper part of the reach-bar by means of any usual and suitable pivoting device.

When the seat is in its proper position, the lever D should be just within convenient reach of the driver or operator. By means of this lever D it will be evident that by a movement of the same the pole C will be

swung partly around on its pivot by reason of the link h remaining stationary, carrying the yoke and reach-bars with it, since both reach-bars are connected by means of the yoke E , and as the plow-beams are attached to said reach-bars by means of the clevis F the said plow-beams will be moved parallel with the forward end of the reach-bar and parallel with each other. 75

By means of the lever M and chain w the rear end of each plow-beam can be either elevated or lowered, thereby causing the shovels to enter the ground to a depth corresponding with the position of each plow-beam, and in this way effectually regulating the depth of cut. 80

The levers N are below the driver's seat, on each side thereof, and can thereby be easily controlled by the operator. 85

Since the chains w are attached to and supported by the arm t' , and since the plow-beams are in turn supported by these chains, it follows, as before mentioned, that the support 90 offered the plow-beams is a very elastic one.

The usual doubletress are preferably pivoted to the pivoting-pin of the pole C , and to each end of this doubletree is attached the usual whiffletrees, to which the team is harnessed. 95

Having now described my invention, what I claim, and desire to secure by Letters Patent of the United States, is—

1. In a wheeled cultivator, the combination 100 of the yoke and the plow-beams hinged at their forward ends to said yoke with the reach-bars pivoted at their forward ends to said yoke and their rear ends to the axle, and each plow-beam flexibly suspended at its forward 105 end, for the purposes set forth.

2. In a wheeled cultivator, a pair of reach-bars pivotally attached to the axle at their rear ends and pivoted at their forward ends to a yoke E , cultivator-beams carrying the 110 usual knives and hinged to the yoke so as to be capable of moving only at right angles to the plane of said yoke, and a supporting-chain for supporting each end of said yoke, all arranged and adapted to operate substantially 115 as set forth.

3. In a wheeled cultivator, the yoke with the plow-beams hinged at their forward ends to said yoke and reach-bars pivoted to said yoke at their forward ends, in combination 120 with a ratchet and lever and suspending-chains attached at one end near the front end of the plow-beams and at their other end to said lever, whereby the front ends of the plow-beams may be raised and lowered, substantially as set forth.

4. The combination, with the axle, of the frame-work attached to the same, the pole C , pivoted within said frame, the lever D , pivoted to said pole and connected to the frame, 130 the reach-bars pivoted to said axle, the plow-beams hinged to the yoke E , and the connecting-rod connecting said pole and said reach-bars, substantially as set forth.

5. The combination, with the axle, of the frame attached thereto, the reach-bars pivoted to said axle and supported by means of chains, and the plow-beams hinged to the yoke, and 5 supported at their rear ends by means of chains attached to an elastic supporting-crane, substantially as set forth.

6. The combination, with the axle, of the reach-bars pivoted thereto and supported by 10 means of chains attached to a locking-lever and the plow-beams hinged to the yoke and supported by means of chains at their forward ends, also attached to said locking-levers, for the purposes set forth, substantially as de- 15 scribed.

7. In a wheeled cultivator, a pole C, pivoted to the main frame of the same, and the lever D, pivoted to said pole and connected to the said frame, in combination with the reach-bars pivoted to the axle and the plow-beams 20 hinged at their forward ends to the yoke E, substantially as set forth.

8. In a cultivator, the combination of the wheels, the pole C, pivoted within the main 25 frame, the lever D, pivoted to said pole C and connected with said main frame, the connecting-rod connecting said pole with one of the reach-bars, the reach-bars pivoted to the main axle at their rear ends and at their forward

ends to a sleeve surrounding the yoke E, connecting the forward ends of the reach-bars, the plow-beams hinged at their forward ends to said yoke E on each side of said sleeve, the supporting-chains for the forward ends of the reach-bars and the rear ends of the plow-beams, and the shovels secured to said plow-beams, substantially as described. 30 35

9. In a wheeled cultivator, the combination, with the reach-bars pivoted to the axle and suspended at their free ends, of the yoke E, 40 also suspended on the reach-bars, and plow-beams hinged to the yoke E at their forward ends and suspended at their rear ends by means of chains, substantially as set forth.

10. In a wheel-cultivator, a yoke and the 45 plow-beams hinged at their forward ends to said yoke, in combination with a toothed sleeve upon both ends of the yoke and interlocking with the hinge of said plow-beams, whereby the space between the plow-beams 50 may be changed.

In testimony whereof I affix my signature in presence of two witnesses.

EDWIN CHILDREN.
